UNITED STATES PATENT OFFICE.

ANTON DIEMER, OF STUTTGART, AND ERNST DURST, OF CANNSTATT, GERMANY, AS-
SIGNORS TO ROBERT BOSCH AKTIENGESELLSCHAFT, OF STUTTGART, GERMANY.

ELECTROMAGNETIC SOUNDING DEVICE.

Application filed September 26, 1925, Serial No. 58,873, and in Germany November 23, 1923.

- In the buzzer sounding devices an armature, which cooperates with one or more sound-disks, is caused to vibrate by means of electromagnetic action.
- 5 In the known sounding devices of this kind the armature is rigidly connected to a spindle, which spindle is guided at two points, for instance, at a sound disk and at a leaf-spring, or at a membrane and at a 10 guide of the casing. Now it is difficult or at least expensive to arrange the connection line of the two guiding points in such a manner that the buzzer armature is caused to set exactly vertically on the pole surfaces of the 15 magnet. If the armature does not move in exactly vertical direction, the danger exists that said armature first rests only with one edge or corner on the poles and that the entire attractive force of the buzzer magnet 20 then tends to tilt the armature around the resting point as a pivot; the consequence of this being that the guiding device of the armature is jammed and twisted. It is always desirable that the armature shall not 25 begin to rest on the magnet with one edge only but that contact between all parts of the cooperating surfaces of the magnet and armature shall be made simultaneously and with a decided impact.
- 30 According to the present invention the before-mentioned drawback is obviated by connecting the armature with its guide in such a manner as to be movable in all directions, so that said armature can adjust itself 35 automatically parallel to the pole surface. This universal adjustability is effected by providing ball-cups on the armature and its guide, said parts being temporarily or constantly pressed against each other with only 40 such a pressure that unbalanced impacts between the armature and magnet caused by the unsymmetric setting of the armature will effect an automatic adjustment of the armature.
- 45 In the accompanying drawing one form of construction of the subject-matter of our invention is illustrated by way of example in cross-section.
- The plate-shaped armature 1 of a buzzer-horn is guided approximately vertically to the pole-surfaces of the buzzer electromagnet 2 by reason of the spindle 3, carrying said armature, being secured to the sound-plate 4 of the buzzer-horn and to a plate-spring 5, and by reason of the ball and socket 50 joint connections hereinafter more fully referred to.
- The armature 1 is supported by the spindle 3 and held thereby, since it is pressed against the upper end of said spindle by means of a screw 6, passing through the entire length of the spindle and a nut 7, riveted into the plate-spring 5. In order to insure a vertical setting of the armature 1 on the magnet 2, the armature constructed according to this invention is provided with a ball-cup 9, which rests on the ball-shaped end of the spindle 3. Furthermore a metal plate 8 having a semispherelike projection is inserted into the armature, the ball cup of the armature 1 and the sphere of the metal plate having the same centre. The semispherelike extension of the metal plate 8 engages with the correspondingly shaped lower face of the nut 7. An armature 75 mounted in this manner adjusts itself automatically parallel to the pole surface when at the assembling of the device the nut 7 is not fully screwed home but is tight enough so that the friction between the spherical parts is sufficient to hold the armature in the positions to which it may be moved when it strikes the magnet during operation of the device. After a short trial operation, the armature adjusts itself correctly 80 and this adjustment can be constantly maintained by tightening the nut. Another shorter method of adjustment is as follows: If at first the armature is tilted or inclined with reference to the magnet-poles, 85 so that it first contacts with the pole-faces of the magnet at one side of the armature-rim, a further movement of the armature toward the magnet will serve to adjust it on the ball and socket joint connection until 90 the armature face opposite the pole-faces is parallel thereto and lies flat at all points against said pole-faces. At this point of the adjusting movement the screw 6 is tightened so as to make this ultimate position of the parts permanent. Thereafter 95 there will be no possibility of a tilting movement of the armature with respect to the pole faces, and the device is ready for accurate operation. The assembling of the buzzer horn is simplified and made more economical in this manner.
- We claim:
1. An electromagnetic sounding device comprising, in combination, an electromag- 110

- net, an armature adapted to be set in vibration by said electromagnet, means, including a sound disk adapted to be set in vibration by said armature, for supporting said armature for movement substantially perpendicularly to the plane of the pole faces of said electromagnet, such supporting means including means effective through contact of the armature with the pole faces of said electromagnet for adjusting said armature parallel to said pole faces.
2. An electromagnetic sounding device comprising, in combination, an electromagnet, an armature adapted to be set in vibration by said electromagnet, means, including a sound disk adapted to be set in vibration by the armature, for supporting said armature for movement substantially perpendicularly to the plane of the pole faces of said electromagnet, such supporting means including a spindle adjustably supporting said armature for angular movement relative to the pole faces of said magnet whereby the armature will be adjusted parallel to said pole faces through contact therewith.
3. An electromagnetic sounding device, comprising in combination an electromagnet, an armature set in vibration by said
- electromagnet, a sound disk set in vibration by said armature, a spindle for said armature and a ball and socket joint connection between said spindle and said armature, said connection allowing the armature to be adjusted parallel to the pole faces of said electromagnet, and means for securing the armature in adjusted position on said spindle.
4. An electromagnetic sounding device comprising, in combination, an electromagnet, an armature adapted to be set in vibration by said electromagnet, a support for said armature permitting the vibratory movement of said armature, a vibratory sound disk set in vibration by said armature, and means effective through movement of said armature automatically adjusting said armature parallel to the pole faces of said electromagnet.
5. An electromagnetic sounding device as set forth in claim 4 and having manually operated means for securing the armature in its adjusted position in parallelism to the pole faces of said electromagnet.

In testimony whereof we have hereunto affixed our signatures.

ANTON DIEMER.
ERNST DURST.
